WELL CLEANING APPARATUS

Hugh A. Montgomery, Houston, Tex.

Application May 7, 1940, Serial No. 333,738

1 Claim. (Cl. 166—16)

This invention relates to new and useful improvements in well cleaning apparatus.

It has been found advantageous to introduce various solvents, acids, and other chemicals into well casings and/or tubings to reduce and eliminate the deposition of paraffin. A common practice is to introduce a solvent or reagent into the well bore at intervals to dissolve or clean out any paraffin which may have deposited on the wall of the well casing or the well tubing. However, this solvent or reagent has been introduced into the upper part of the well and allowed to flow downwardly. Obviously, to properly wet the wall of the well casing or tubing with the reagent, a sufficient quantity must be introduced to allow some to flow into the oil sands. This is very detrimental to the well and often causes a well to cease flowing altogether.

One object, therefore, of this invention is to provide an improved well cleaning apparatus, whereby the solvent or reagent may be introduced into a section or portion of the well below the upper end thereof.

Another object of the invention is to provide an improved well cleaning apparatus, whereby the solvent or reagent may be introduced in any desirable amount directly into the well stream flowing through the well tubing, and whereby the amount and frequency of introduction of the solvent or reagent may be positively and readily controlled.

A further object of the invention is to provide an improved well cleaning apparatus which is simple in structure, and which may be readily disconnected from the tubing string to allow the latter to be withdrawn from the well bore.

Still another object of the invention is to provide an improved well cleaning apparatus which may be attached to a section of ordinary tubing string, thereby eliminating the necessity of special tools or operations and reducing the cost of the apparatus.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a schematic view of a well cleaning device, constructed in accordance with the invention, mounted on a tubing string in a well bore,

Figure 2 is a longitudinal sectional view, showing the structure of the connecting member,

Figure 3 is a view in elevation taken at right angles to Figure 2, and

Figure 4 is a horizontal, cross-sectional view taken on the line 4—4 of Figure 3.

In the drawing, the numeral 10 designates the tubing string which is lowered into a well bore or casing. An elongate valve body 11 of blister-like shape is welded, or otherwise suitably fastened, to the outside of one tubing section 12 of the tubing string 10 at any point at which it is desired to introduce solvents or reagents, and a check valve 13 is positioned therein. Any desirable type of check valve may be used in the valve body. It has been found advantageous to use the valve and valve body illustrated in the drawing. The body 11 is formed with a substantially semi-circular cross-section, and has its upper and lower ends rounded. The rounded ends greatly reduce the possibility of the body's catching on a collar or some other obstruction in the well bore as the tubing is raised or lowered. A longitudinal bore 13' is provided in the valve body. The lower portion of the bore 13' is reduced and formed with internal left-hand screw threads 14. The threads 14 receive and engage the left-hand screw-threaded lower end 15 of a string of relatively small tubing or pipe 16. The left-hand screw threads, connecting the pipe 16 to the valve body, allow the pipe to be disconnected by right-hand rotation and withdrawn from the well bore, leaving the tubing 10 free to be withdrawn.

A counterbore 17 extends downwardly from the lower end of the bore 13', and terminates at a point spaced from the lower end of the valve body. The upper end of the counterbore 17 carries internal screw threads 18 for receiving an annular internally screw-threaded valve seat 19. A valve ball 20 is confined within the counterbore between the valve seat 19 and a coil spring 21 positioned in the lower portion of the counterbore. Thus the valve ball is constantly urged upwardly by the spring 21 to engage the seat 19 and shut off communication through the seat and the bore 13'. Pressure acting downwardly through the valve 13 will unseat the valve ball and allow fluids to flow downwardly, while pressure acting upwardly upon the valve will only serve to seat the valve ball tighter against the seat 19.

A radial port 22 extends from one side of the counterbore 17 at a point below the valve ball 20 to the outside wall of the tubing section 12, and

registers with a reduced opening or orifice 23 extending through the side wall of the section. With this structure, fluid may be forced downwardly through the pipe 16, the valve seat 19, the counterbore 17, the port 22, and the orifice 23, into the well stream flowing through the tubing 10 and tubing section 12. The pipe 16 is formed of the usual sections or lengths 24, which are coupled by means of collars 25. The pipe extends from the upper end of the valve 13, up the well bore to a pump 26 situated at or adjacent the top of the well bore. Any suitable type or design of pump, such as a steam or gas pump, a motor pump, or a hand pump, may be used at the upper end of the pipe 16. If the well is being pumped, the pump 26 may be connected to the usual pump jack so as to operate with the latter. Also, if desired, a second check valve (not shown) may be placed in the pipe 16 at a point adjacent the pump 26 to protect the apparatus in the event the valve 13 is held open by foreign matter entering between the ball 20 and the seat 19. The second check valve is not necessary to the operation of the device, but merely furnishes an additional safeguard against the leakage of the well fluid upwardly through the pipe 16. In addition, a pressure gauge (not shown) may be connected to the pipe 16 to indicate the pressure present therewithin.

Suitable solvents or reagents may be pumped down the pipe 16, through the valve 13 and the orifice 23, into the well stream flowing through the tubing string 10. The solvent or reagent will be carried toward the top of the well by the flowing well stream, and will loosen and dissolve the paraffin deposits present on the inside wall of the tubing string.

Manifestly, the apparatus as described hereinbefore, offers many advantages. The solvent or reagent fluids used will remain standing in the pipe 16 at all times, due to the fact that it will not exert sufficient pressure to open the valve 13 and drain into the tubing section 12 against the well pressure and the spring 21. Under these conditions, as much or as little fluid as deemed suitable may be pumped through the pipe into the well stream. This allows the apparatus to be used under the widely varying conditions en-

countered in different wells. The injection of the fluid is positive, due to the action of the pump 26, and is carried out in such a manner as to cause the fluid to be carried upwardly by the well stream or flow. Obviously, the valve body 11 may be placed at any desirable point in the tubing string 10, so that the tubing will be treated from any such point to the surface of the ground.

The device may be used to inject fluid solvents, acids, reagents, hot water, steam, and other desirable fluids, into the tubing of an oil well or any other type of well. The invention is not to be limited to use with paraffin solvents.

As the amount of treating fluid and the length of treatment usually varies from well to well, no particular operating procedure may be stated. The device may be operated continuously or intermittently as the particular well requires. Various changes, alterations and modifications may be made in the size, shape and arrangement of the herein described elements, within the scope of the appended claim.

What I claim and desire to secure by Letters Patent is:

25 A cleaning apparatus for wells including a conductor formed with a passageway through which the well stream flows, and provided with an inlet communicating with the interior of the passageway, a hollow blister-like body having its 30 marginal edges rounded and merging into the periphery of the conductor and provided with a port communicating with said inlet of the conductor means detachably connected to the body for conveying a cleaning agent into the body and 35 therethrough into the well stream, said inlet being below the top of the well whereby the agent upon encountering the well stream will be carried upwardly by the stream, and said body being intimately welded at its margin to the 40 periphery of the conductor to prevent the escape of the cleaning agent through the joint between the body and conductor, and a check valve in and movable longitudinally of the body and located above the port thereof, to prevent the well 45 stream from entering the cleaning agent conveying means.

HUGH A. MONTGOMERY.
